METHODS AND APPARATUS FOR SEPARATING SOLIDS HAVING DIFFERENT SPECIFIC GRAVITIES

Klaas F. Tromp, Bilthoven, Netherlands

Application July 29, 1953, Serial No. 371,105

Claims priority, application France August 6, 1952

5 Claims. (Cl. 209—172.5)

This invention relates to methods and apparatus for separating solids having different specific gravities in a tank containing a suspension whose density increases in a direction from the level of the suspension to the bottom of the tank, wherein the middlings, i. e. the suspended solid products, isolated from the floating and the sinking products, are carried, by means of substantially horizontal, rectilinear currents produced at various heights in the bath, towards outlet openings of the tank, through which they are discharged together with said currents of suspension. Owing thereto, said middlings are prevented from accumulating in the separation zone of the bath, it being understood that such accumulation would impair and even prevent the settling of the sinks.

Hereinafter reference will be had to the washing of run-of-mine coals, although the invention is not limited thereto, and the comminuted solid phase of the suspension will be referred to as "sand."

In known apparatus of the type referred to, the bony coals, i. e. the middlings, are discharged by causing the current of suspension laden therewith to divert from its substantially horizontal path, either in upward or in downward direction. However, I have found that either method has certain drawbacks.

If said current is caused to divert in upward direction, then, owing to the fact that its density increases in downward direction, suspension of its top layer, having a relatively low density, will be the first to be discharged and will naturally be supplemented by other suspension of the same layer and not, or only very partly, by suspension of the lower layers, whose densities are relatively high. That is to say, the discharge of suspension of the lower layers will lag behind that of suspension of the top layer, the consequence being that the discharge of the bony coals in the lower layers is retarded. Moreover, sand settling from the top layer will reach layers whose velocities of flow are lower than that of the top layer, so that the densities of said lower layers will increase. Stated with other words: owing to the retarded discharge of the lower layers of suspension, the densities of these layers will increase. This will again reduce the velocities of flow of said layers and thereby still further increase the accumulation of bony coals therein, thus seriously interfering with the settling of the slate, i. e. the sinks.

In case the direction of flow of the current of suspension carrying the bony coals is caused to divert in downward direction with a view to discharging said current from the receptacle, a similar phenomenon will occur. That is to say, the bottom layer of relatively high density will be the first to be discharged and the higher layers of lower density will lag behind. Owing thereto, the settling of sand from said higher layers will gradually reduce the densities of said layers, whereby the discharge thereof will still further be interfered with.

The retardation of the discharge of the middlings in the higher layers is a drawback especially in the wet cleaning of coals, since the amount of bony coals of rela-

2

tively low specific gravity generally considerably exceeds the amount of bony coals of relatively high specific gravity, so that by far the greater part of the middlings is carried by the higher layers of the suspension. Besides, at the rear end of the tank the increase, in downward direction, of the density of the suspension in the higher layers exceeds that in the lower layers, and this phenomenon also favorably affects the accumulation of bony coals in said higher layers.

10 The main object of my present invention is to materially reduce the above disadvantages. With this object in view, I suggest that the top layer of the current of suspension carrying the middlings is discharged in horizontal or in upward direction, and that the lower layer of said current is discharged in downward direction. The result thereof is that the causes of the aforesaid progressive interference with the discharge of the middlings are for the greater part suppressed. As a matter of fact, any increase of the density of the lower part of the current discharged in upward direction will be compensated for by a decrease of the density of the upper part of the current discharged in downward direction.

I shall now proceed to describe my invention in further details with reference to the annexed diagrammatic drawing, in which Figures 1, 2 and 3 illustrate three different embodiments thereof. Fig. 1a shows on an enlarged scale a detail of the embodiment illustrated in Fig. 1, and Fig. 2a is a plan view of that portion of the apparatus shown in Fig. 2 which is situated below the plane A—A.

25 In the embodiment shown in Figs. 1 and 1a, the tank 1 has parallel, vertical side walls, a horizontal bottom 2, a downwardly sloping front wall 3, and a vertical rear wall 4 having an upwardly and rearwardly inclined weir 5. The lower part of the tank accommodates the horizontal portion of the lower part of an endless drag conveyor 6 driven in clockwise direction by suitable means not shown. The lower part of said conveyor sweeps the bottom and the front wall of the tank, and the upper part thereof sweeps a false bottom 7 running in parallel relation with the front wall 3 and suitably spaced therefrom.

30 The lower part of a second conveyor 8, driven in counterclockwise direction by suitable means not shown, has a horizontal front portion sweeping the surface 9 of the suspension contained in the receptacle, the rear portion of said lower part sweeping an upwardly and rearwardly inclined, perforated sheet 10, which has a width substantially equal to the inner width of the tank and whose lower portion 11 extends through a suitable distance below the surface of the bath.

35 Provided some distance vertically above the surface of the bath and the false bottom 7, are pipes 12 for supplying relatively low density suspension to the tank, said pipes being perforated so as to evenly distribute said suspension through the full width of the bath. By means of curved guide sheets 13, said suspension is also evenly distributed through the full height of that portion of the bath which is situated above the conveyor 6.

40 A horizontal, perforated pipe 14 for the supply of relatively heavy suspension to the space confined by the lower and the upper parts of the conveyor 6 is located above the surface 9 of the bath a small distance behind the upper edge of the front wall 3 of the tank.

45 The rear end of the bottom 2 is spaced some distance from the vertical rear wall 4, and opening from below into the slot so formed is a vertical conduit 15 connected, through an elbow 16, with a riser provided with a weir 17 situated a substantial distance below the surface 9 of the bath. The level of said weir is adjustable in a manner well known in the art.

The weir 5 is pivoted as at 18 about a transverse horizontal axis and is provided at its front end with a curved, downwardly extending flange 19 permanently in contact with the top edge of the rear wall 4 so as to prevent leakage of suspension in any position of the weir 5 within the range of adjustment thereof, see Fig. 1a. The weir 5 supports an arm 36 hinged about a transverse horizontal axis and secured to which is a baffle plate 20 immersed in the top layer of the bath.

A partition 21 is provided between the two parts of the conveyor 6 immediately in front of the rear roller about which said conveyor is passed. Said partition acts, in cooperation with the scrapers of the conveyor, as a sluice.

The numeral 22 designates a chute through which run-of-mine coals can be fed to the bath, and the numeral 23 indicates a horizontal dewatering screen mounted with its front end vertically below the top of the conveyor 8 and cooperating with sprayers 23a. The front end of a second horizontal dewatering screen 24, cooperating with sprayers 24a, is disposed vertically below the weir 17.

The top edge of the front wall 3 of the tank is indicated by 25 and vertically below the same is the rear end of a horizontal screen 26 cooperating with sprayers 26a.

Mounted vertically below the front end of the screen 24 is a boot 27 connected at its bottom to the suction side of a pump 28 for feeding the pipe 14, and another boot 29 serves to receive the overflow of boot 27. The bottom of boot 29 is connected to the suction side of a pump 30 for feeding the pipes 12.

The lower end of the vertical conduit 15 is connected, through a valve 31, to a compressed air supply pipe not shown.

The method of operating the apparatus described with reference to Figs. 1 and 1a is as follows.

If run-of-mine coals are supplied to the bath in the tank 2 through the chute 22, the pure coals, i. e. the product of relatively low specific gravity, will float on the surface of the suspension. Said coals will be removed from the bath, across the plate 10, by the lower part of the conveyor 8 and discharged onto the screen 23. The sand still adhering to these coals will be removed therefrom by the jets of pure water from the sprayers 23a.

The products of relatively high specific gravity, i. e. the slate, will settle on the false bottom 7 and be removed therefrom by the upper part of the conveyor 6 so as to fall onto the bottom 2 of the tank to be discharged by the lower part of said conveyor.

The bony coals, i. e. the products whose specific gravities have values intermediate those of the pure coals and of the slate, will be suspended in the suspension above the upper part of the conveyor 6. They are carried towards the rear wall of the tank both by said upper part of the conveyor 6 and by the suspension flowing towards the rear wall 4 of the tank. The bony coals of relatively high specific gravity will, on reaching this wall, be discharged, together with the suspension wherein they are suspended, through the conduit 15, 16 and over the weir 17, so as to fall onto the dewatering screen 24, on the rear portion of which they are washed by the water from the sprayers 24a and thus freed from the adhering sand.

That part of the current which carries the bony coals of relatively low specific gravity is discharged by the weir 5. If this weir assumes its highest position shown in Fig. 1a, the baffle 20 assumes a position above the surface of the bath, so that the surface layer of said current, i. e. the layer carrying the bony coals of the lowest specific gravity, will be discharged from the tank. In its lowest position as illustrated in Fig. 1, the baffle 20 forms a bar to the discharge of said surface layer, so that the next lower layer of suspension having a some-

what higher density is discharged together with the specifically somewhat heavier bony coals carried thereby.

The suspension overflowing the weir 5 and the bony coals carried thereby fall onto the screen 24 (but somewhat beyond the suspension discharged by way of the conduit 15, 16) on which said coals are dewatered and washed by the water from the sprayers 24a.

The slate discharged from the tank, together with a certain amount of suspension, by the lower part of the drag conveyor 6 across the top edge 25 of the front wall 3, is received by the dewatering screen 26, the rear portion of which serves for removing the suspension. On the front portion of said screen, the slate is washed by water from the sprayers 26a so as to be freed from the adhering sand.

The relatively high density suspension discharged by the weir 17 is received by the boot 27 and is returned to the tank 1 by the pump 28 and the pipe 14. The level of the weir 17 should be so adjusted that the amount of suspension overflowing per unit of time exceeds the capacity of the pump 28, so that there will always be a certain amount of overflow from the boot 27 into the boot 29, which receives the relatively low density suspension overflowing the weir 5. From the boot 29, the suspension is returned to the tank 1 by means of the pump 30 and the pipes 12, which distribute the suspension through the full width and height of the bath above the level of the upper part of the drag conveyor 6.

It will be understood that in the apparatus just described with reference to Figs. 1 and 1a of the drawing, by far the greater part of the relatively high density suspension supplied by the pipe 14 will flow below the false bottom 7 and over the top edge of the partition 21 to be discharged by way of the conduit 15, 16, only a very small part thereof being discharged, together with the slate, over the top edge 25 of the front wall 3.

The bony coals of relatively high specific gravity will float on the surface of the current of the relatively high density suspension. The scrapers of the drag conveyor 6 assist in carrying said bony coals towards the conduit 15, 16, but since the specific gravity of these coals is lower than that of the relatively high density suspension, the flow of the suspension in the conduit 15, 16 may not be strong enough to carry the entire amount of said coals, and especially of the larger lumps thereof, towards the weir 17. Consequently, it may be desirable for the suspension in the conduit 15 to be diluted with relatively low density suspension from the tank. With a view thereto, the amount of suspension discharged by the weir 17 per unit of time may be allowed to exceed that supplied by pipe 14, and this can be realized by permitting the suspension in the boot 27 to overflow into the boot 29. The amount of this overflowing suspension is practically equal to the amount of relatively low density suspension, which is discharged, together with the relatively high density suspension, through the conduit 15, 16. Since the boot 27 functions as a thickener and provided it is suitably dimensioned, it is possible for the densities of the suspensions returned to the tank 1 by means of the pumps 28 and 30 to be kept substantially constant.

With a view to reducing the density of the suspension in the conduit 15 and immediately above the inlet thereof, i. e. at the rear of partition 21, air may be blown into said conduit by opening the valve 31. Since the floating pure coals are removed from the fluid as at 11, it will be appreciated that the disturbance created by said air cannot interfere with the purity of said floats, and a similar remark applies to the sinks (slate).

Turning now to Figs. 2 and 2a, it will be seen that the vertical side walls of the rear part of the tank 1, i. e. of the part located vertically below the sheet 10 and above the drag conveyor 6, converge, and also that a wedge member 36' is provided centrally between said converging side wall portions, said wedge member pointing to the front wall of the tank. Owing to this construction,

the velocity of flow of the fluid in the region of the weirs 5 and 17 is considerably increased, whereby the discharge of the bony coals, and especially those carried by the lower layers of the upper current of suspension, is favorably affected.

The sheet 10 of the apparatus illustrated in Fig. 2 is imperforate, so that said sheet, cooperating with the scrapers of the drag conveyor 8, acts as a sluice for removing the top layer of the suspension in the tank 1 and discharging the same, together with the pure coals, onto the dewatering screen 23.

Owing to the fact that the submerged portions of the pure coals displace an equivalent volume of fluid, and assuming the level 9 of the bath to be constant, the amount of suspension discharged by the drag conveyor 8 will be variable and decrease as the amount of pure coals increases. This has the drawback that the amount of fluid overflowing the weir 5 will also vary. With a view to avoiding this drawback, it is suggested to measure the amount of fluid passing the screen 23 per unit of time and to increase the speed of the conveyor 8 if the measured amount is too small, and vice versa. To this end, the fluid passing the screen 23 may be collected in a receptacle 37 (see Fig. 2) having a bottom opening provided with a measuring disk 38. If now the level of the fluid in said receptacle and thereby the amount of fluid discharged per unit of time, is controlled by a float 39, the speed of the motor for driving the conveyor can be varied accordingly by apparatus well known in the art.

Fig. 3 illustrates an installation wherein the drag conveyor 6 shown in Figs. 1 and 2 is substituted by a boot 32 from which the slate may be removed in known manner by a bucket elevator not shown, or by a goose neck tube 33, in whose vertical portion the upward speed of flow should be relatively high. With a view thereto, said goose neck is provided with a compressed air inlet 34, so that it can function as an air lift, if so desired. The fluid thus raised, after passing the screen 26, is returned to the throat of the boot 32, the consequence being that the speed of flow in the gooseneck 33 may be increased at will whilst the fluid in the boot 32 remains practically stagnant. An installation of this type is suitable, for instance, for cleaning relatively small sized coals.

It will be appreciated that it is essential for the density of the suspension in the boot 32 to be uniform throughout the height thereof. In this respect, the fact that said boot is fed with relatively high density suspension is a favorable feature. Nevertheless, it may be desirable, in order to maintain the uniformity of the density, to provide for a downward flow of fluid in the boot 32, and this can be realized by drawing a certain amount of the suspension passing the dewatering screen 26 into the suction pipe of the pump 28 by opening a valve 35, which amount should be smaller, per unit of time, than the amount of relatively high density suspension supplied to the tank 1 by way of the pipe 14, so that a substantially horizontal flow of relatively high density suspension in the tank 1 vertically above the boot 32 and, as a consequence, overflow of said suspension into the conduit 15 are ensured. This suspension is, as described hereinbefore, mixed with a sufficient amount of relatively low density suspension, in order to ensure that the bony coals floating thereon may settle in the conduit 15. The said amount of relatively low density suspension is practically equal to the amount of fluid overflowing boot 27 and can be controlled by vertically adjusting the weir 17.

By periodically operating the hinged baffle 20 so as to check the surface current of suspension in the same manner as described with reference to Fig. 1, the next lower, somewhat denser current of fluid together with the bony

coals carried thereby is allowed to be discharged. In a similar manner, periodical operation of a hinged baffle 40 so as to set the same in a vertically upward position will periodically check the lower layer of the current of suspension of relatively high density, thereby causing the next higher, less dense fluid together with the bony coals suspended therein to be discharged from the tank.

Obviously, the means for removing the surface layer of suspension together with the pure coals floating thereon as illustrated in Fig. 2, i. e. the imperforate sheet 10, could substitute the perforated sheet 10 shown in Figs. 1 and 3, and vice versa.

What I claim is:

1. A process for separating solid materials having different specific gravities by means of a suspension contained in a tank, consisting in creating substantially horizontal rectilinear currents in said suspension by supplying thereto suspensions of different densities at different heights at the front end of the tank, removing the floats and the sinks from the tank, hydraulically discharging the middlings by deflecting the upper part of the suspension with the middlings suspended therein in an upwardly inclined direction at the rear end of the tank and by deflecting the lower part of the suspension with the middlings suspended therein in downward direction at the rear end of the tank.

2. A process as claimed in claim 1, consisting in supplying a relatively low density suspension to the upper part of the tank, supplying a relatively high density suspension to the lower part of the tank, so that the amount of relatively high density suspension supplied to the lower part of the tank is smaller, per unit of time, than the total amount of suspension deflected in downward direction.

3. Apparatus for separating solids having different specific gravities, comprising a tank, means for supplying the solid materials having different specific gravities at the front end of the tank, means for supplying a suspension of relatively low and a suspension of relatively high density at an upper and at a lower level, respectively, of the tank at the front end thereof in a substantially horizontal direction and through substantially the full width thereof, means for discharging the suspension with middlings suspended therein from the tank both at a relatively high and at a relatively low level, an upwardly and rearwardly inclined plate having its front edge submerged below the normal level of the bath in the tank, mechanical means for removing floats from the bath across the said plate, means for removing sinks from the bath, and at least two weirs at different levels and at the rear end of the tank for discharging the suspension with middlings suspended therein, the lower weir communicating with a bottom opening of the tank by a U-shaped duct.

4. Apparatus in accordance with claim 3, wherein the upper weir is hinged about a horizontal axis transversely to the longitudinal axis of the tank, and is associated with means for imparting oscillatory movement thereto.

5. Apparatus in accordance with claim 3, wherein the rear end portion of the tank has rearwardly converging side walls.
